UNITED STATES PATENT OFFICE.

JOSEPH BELANGER, OF BUTTE, MONTANA.

WINDOW.

1,359,221.

Specification of Letters Patent. Patented Nov. 16, 1920.

Application filed February 28, 1920. Serial No. 362,101.

To all whom it may concern:

Be it known that I, JOSEPH BELANGER, a citizen of the United States, and a resident of Butte, county of Silver Bow, Montana, have invented certain new and useful Improvements in Windows; and I do hereby declare that the following is a full, clear, and exact description of the invention, such as will enable others skilled in the art to 16 which it appertains to make and use the same.

The present invention relates to windows and more particularly to a sash extension for windows whereby the windows and 15 sashes therefor may be swung inwardly within a room of a building, so that access may be readily gained to either side of the windows for the purpose of cleaning or repairing the same.

20 An object of the invention is to provide a sash extension for either stationary or vertically slidable sashes which may be easily and readily applied thereto without any material changes or alterations to the 25 window sash or window casing.

With the above and other objects in view which will hereinafter appear as the description continues, the invention consists of the 30 novel features of construction, combination and formation of parts as will be herein-after more fully described and particularly pointed out in the appended claims.

In the accompanying drawings:

Figure 1, is a front elevation of a window 35 and casing therefor having vertically slideable window sashes with an embodiment of the present invention applied thereto.

Fig. 2 is a fragmental vertical section through the same on a slightly enlarged 40 scale.

Fig. 3 is a horizontal section taken through the window and the window casing on an enlarged scale.

Fig. 4, is an enlarged detail section showing the sash extension as applied to the window sash and,

Fig. 5, is a detail perspective view of the sash extension.

Referring now more particularly to the 50 accompanying drawings wherein like and corresponding parts are designated by similar reference characters throughout the several views.

The window as herein shown comprises a 55 casing of the usual construction consisting of

a sill 1, a top 2 and sides 3 the latter of which are of the usual hollow construction so that the weights 4 may travel therein. Slidably mounted within the window casing is a lower sash 5 and an upper sash 6 each having a pane of glass supported therein. The sides 7 of the sashes 5 and 6 have connected thereto in the usual manner the sash cords 8 and the latter being connected to the weights 4 so as to retain the window 65 sashes in their moved positions. The opposite side members 9 of the window sashes have connected thereto the sash extensions, embodying the present invention, and these sash extensions have connected thereto the 70 sash cords 10 and the latter being connected to the weights 4 at this side of the window.

The sash extension as herein shown is preferably made of sheet metal consisting of a stationary member 11 which is substantially of a U-shaped configuration in cross section and a movable section 12 which is hingedly connected to the stationary section as 13. The medial portion of the stationary section 11 is provided with an inwardly 75 extending projection 14 forming a channel way in which is secured as at 15 one end of the sash cord 10. These sash extensions are adapted to slide in the usual grooves or guide ways formed within the side member 80 3 of the window casing. The sides 9 of the window sashes are adapted to rest within the sash extensions and are retained therein by means of the bolts 16. These bolts 16 extend through the side member 17 of the 85 stationary section 11, through the members 9 of the sashes and the movable section 12 of the sash extension. Each bolt is provided with a winged nut 18 so as to clamp the members 9, 12 and 17 together. When the 90 sash extension is so connected to the sash of the window the latter may be raised and lowered in the usual manner, but when it is desired to gain access to the outer side of the window sash all that is necessary 95 to do is to remove the winged nuts 18 and swing the movable section 12 upon its hinged connection until it assumes a position as better illustrated in dotted lines in Fig. 4. The window sash may be then 100 swung inwardly in the direction of the arrow as shown in Fig. 3 thereby presenting the outer side of window sash within the room. The window sashes are swung upon the sash cords 8 and the sash exten-

105 110

sions at all times remain in position or within the grooves provided within the window casing.

The bolts 16 project through the horizontally extending slots 19 formed within the members 12 and 17 so that the sashes may be laterally adjusted to take up any wear or unevenness and thereby permitting the sash extensions to act as a weather stripping for the opposite sides of the window sashes.

While I have shown the sash extension as applied to a vertically movable window it may be also applied to a stationary window and it may also be made of cast metal, sheet metal or wood as is desired.

Having thus fully described my invention, what I claim as new and desire to secure by Letters Patent is:—

1. The combination with a window casing and a vertically slideable sash arranged therein, a sash cord connected at one side to said sash, a sash extension slidably mounted within casing and adapted to receive the opposite side of said sash, a sash cord connected to said sash extension, said sash extension comprising a stationary section and a movable section having horizontally extending slots therein, fastening elements

adapted to extend through the slots of said members and the sash for detachably and adjustably connecting the sash to said sash extension substantially as and for the purpose specified.

2. The combination with a window casing and a vertically slideable sash arranged therein, of a sash cord connected at one side to said sash, a sash extension adjustably and detachably connected to the opposite side of said sash, a sash cord connected to said sash extension, said sash being adapted to swing upon said sash cord connected at one side thereof when said sash extension is disconnected, substantially as and for the purpose specified.

3. A sash extension for windows comprising a main section adapted to slide within the window casing, means for connecting a sash cord to said main section, a swinging section comprising a plate hingedly connected to one side of said main section and means for detachably and adjustably connecting said section to the sash of the window.

In witness whereof I have hereunto set my hand.

JOSEPH BELANGER.
